UNITED STATES PATENT OFFICE.

CARL G. PRITCHARD, OF WARREN, OHIO, ASSIGNOR TO THE HARRIS AUTOMATIC PRESS COMPANY, OF NILES, OHIO, A CORPORATION OF OHIO.

DELIVERER FOR PRINTING-PRESSES.

1,309,544.

Specification of Letters Patent.

Patented July 8, 1919.

Application filed February 16, 1915. Serial No. 8,523.

To all whom it may concern:

Be it known that I, CARL G. PRITCHARD, of Warren, in the county of Trumbull and State of Ohio, have invented certain new and useful Improvements in Deliverers for Printing-PresSES; and I do hereby declare the following to be a full, clear, and exact description of the invention, such as will enable others skilled in the art to which it

10 appertains to make and use the same.

The primary object of this invention is to provide simple and highly efficient means for discharging stock from a printing press.

And a further object is to provide a deliverer capable of being used in a restricted delivery space, and especially adaptable to multicolor printing presses handling sack tubes, card-board or other relatively stiff paper, rendering the use of complicated conveyors unnecessary and lessening the danger of smearing.

According to my invention each sheet or other article, as it leaves the impression cylinder, enters a guide from which it will be discharged in reverse order when its tail end is free of the press-cylinder.

In the accompanying drawings, Figure 1 is a view in side elevation. Fig. 2 is a front elevation. Fig. 3 is a diagrammatic view 30 showing in dotted lines the various positions occupied by an article as it is being discharged from a press.

Referring to the drawings, 1 designates an impression cylinder; 2 the press frame; 3 and 5 guide- or take-off wheels mounted on a common shaft 4. 5 designates ordinary strippers which are shown in the form of fingers depending from a common rod 6 and extending at their lower ends toward the

40 face of the impression cylinder.

To a cross rod 7 of the press frame are secured upper guides which are shown as being composed each of an inner member 8 and an outer member 9, said members being 45 on substantially parallel lines with each other. They are shown set at a slight angle to a vertical plane passing through the longitudinal axis of the impression cylinder, but they may be set in any desired position.

50 The inner members 8 are shown as overlapping the upper ends of strippers 5, while the outer members 9 are carried downwardly beyond said strippers and terminate in outwardly curved portions as indicated at 10.

55 12 designates the lower guides which in con-

junction with the curved portions 10 of the outer members 9 form a guideway for the discharge of the stock. These guides 12 are shown as mounted on a cross-rod 13 and as extending at their inner ends up to shaft 60 4 which carries the take-off wheels 3, while their outer ends are projected downwardly at an angle substantially parallel with the lower ends of the outer members 9 of the upper guides.

65 In practice the sheet printed upon—bag-tubes, or relatively stiff sheets like card-board—is stripped from the press cylinder in the usual way by strippers 5 and passes upwardly into the upper guides, which 70 movement may be limited by adjustable stops 14. The tail of the sheet is swung past the inner ends of the lower guides 12, either mechanically or by momentum, and when free of the press-cylinder the sheet being 75 without support will immediately fall from the upper guides, and by means of the lower guides 12, aided by the lower portions of the upper guide members 10, will be discharged onto a pile or any suitable receiver 80 such as a lay-board 15, or onto a conveyer of any suitable construction. According to the means shown each sheet is reversed, that is, turned upside down, or inverted, being discharged with its printed side up, but it may 85 be discharged in any desired direction after its travel in leaving the cylinder has been arrested and reversed.

Although I have shown fixed guides for directing the sheets in their reversed travel, 90 any suitable means, such as rolls or endless tapes, may be employed to assist in delivering sheets to the desired point.

In the claims appended hereto I have used the word "sheet" as designating the 95 article printed upon, but it will be understood that this term contemplates tubes, such as are used for forming paper bags, as well as any kind of sheet having sufficient inherent stiffness to insure the upward 100 travel of its forward edge into the upper guides so that when its tail is free of the press-cylinder it will be discharged tail end first.

I claim as my invention:

1. In combination with a printing press having a rotary cylinder and means for stripping sheets therefrom, means for controlling the movement of the sheet as it is stripped from the cylinder, and relatively 110

- fixed guiding means coöperating therewith for effecting discharge of the sheet in a reverse position.
2. In combination with a printing press having a rotary cylinder and means for stripping sheets therefrom, fixed guides for controlling the movement of the sheet as it is stripped from the cylinder, and an inclined guide coöperating therewith for effecting discharge of the sheet in a reverse position.
3. In combination with a printing press having a rotary cylinder and means for stripping sheets therefrom, means for arresting the travel of the sheet as it is stripped from the cylinder, and an inclined guide coöperating therewith for effecting discharge of the sheet in a reverse position.
4. In combination with a printing press having a rotary cylinder and means for stripping sheets therefrom, means for receiving and arresting the travel of the sheet as it is stripped from the cylinder and from which it will pass by gravity, and means for effecting discharge of the sheet in a reverse position.
5. In combination with a printing press having a rotary cylinder and means for stripping sheets therefrom, means for receiving each sheet as it is stripped from the cylinder and discharging it tail end first, and fixed guides for reversing the position of the sheet as it passes from said receiving means.
6. In combination with a printing press having a rotary cylinder and means for stripping sheets therefrom, means for receiving each sheet in a substantially upright position as it is stripped from the cylinder and from which it will pass by gravity, tail end first, in a contrary direction, and inclined guides coöperating therewith for effecting discharge of the sheet in a reverse position.
7. In combination with a printing press having a rotary cylinder and means for stripping sheets therefrom, guides into which each sheet is delivered from the cylinder and from which it will pass by gravity, and fixed coöperating guides for reversing the position of the sheet as it passes from said guides.
8. In combination with a printing press having a rotary cylinder and means for
- stripping sheets therefrom, upper guides for receiving the advance end of each sheet and from which the sheet will pass when the tail of the sheet is free of the press cylinder, and guides for coöperating with the first mentioned guides for discharging the sheet, tail end first.
9. In combination with a printing press having a rotary cylinder and means for stripping sheets therefrom, upper guides, set an angle, for receiving the forward end of each sheet, and lower guides for discharging each sheet, tail end first, as it passes from said upper guides.
10. In combination with a printing press having a rotary cylinder and means for stripping sheets therefrom, upper guides comprising inner and outer members, a stop carried by one of said members for limiting the upward movement of the forward end of a sheet discharged from said press cylinder, and lower guides beneath said upper guides for discharging each sheet, tail end first, as it passes from said upper guides.
11. In combination with a printing press having a rotary cylinder and means for stripping a sheet therefrom, an upper substantially upright guide for receiving the sheet after it is stripped, said guide having inner and outer vertical walls, said outer wall extending below said inner wall, and a lower guide extending downward at an angle to said upper guide.
12. In combination with a printing press having a rotary cylinder and a stripper adjacent said cylinder, an upper substantially upright guide for receiving a sheet after it is stripped, said guide having inner and outer vertical walls, said inner wall overlapping said stripper, said outer wall extending below said inner wall and having an angular extremity, and a lower guide extending downward at an angle to said upper guide and parallel with said angular extremity.

In testimony whereof, I have signed this specification in the presence of two subscribing witnesses.

CARL G. PRITCHARD.
